EDGAR H. MORGAN AND CHARLES MORGAN, OF FREEPORT, ILL., ASSIGNEES
TO THE NEW UNION MANUFACTURING COMPANY, OF SAME PLACE.

COFFEE-MILL.

SPECIFICATION forming part of Letters Patent No. 329,065, dated October 27, 1885.

Application filed November 13, 1884. Serial No. 147,813. (No model.)

To all whom it may concern:

Be it known that we, EDGAR H. MORGAN, a resident of Freeport, in the county of Stephenson and State of Illinois, and CHARLES MORGAN, also a resident of Freeport, in the county of Stephenson and State of Illinois, have invented certain new and useful Improvements in Coffee-Mills; and we do hereby declare the following to be a full, clear, and exact description of the invention, such as will enable others skilled in the art to which it pertains to make and use the same.

Our invention relates to improvements in coffee-mills, and is fully described, explained, and claimed in the following specification and shown in the accompanying drawings, in which—

Figure 1 is a view of the mill in perspective, a part of the hopper being broken away to show the internal construction; Fig. 2, a central vertical section of the mill, the drawer being removed and the plane of section passing through one of the braces K, which connect the bowl I and hollow post J; Fig. 3, a bottom plan of the grinding-shell L, and Fig. 4 a side elevation of the cone L" and the parts formed integrally therewith.

In these views, B is a base-plate, preferably of wood; and A, a cast-iron frame, consisting of a top plate and four legs, each of which is provided with a horizontal flange adapted to be screwed to the base-plate. On three sides of the frame A the space between the legs may be cut to any desired form, either plain or ornamental; but the fourth side is formed with a rectangular opening for the admission of a drawer resting on the base-plate, and preferably of such size as to touch the lower face of the top plate of the frame and the inner faces of the legs at the four corners of the frame. This drawer may be of any desired material; but for economy of space, weight, and cost we prefer to make it with a wooden front and sheet-metal sides and bottom, as shown. The sides of the drawer show through the openings between the legs of the frame, and any desired ornamentation may be applied to them.

In the center of the top plate of the frame A is a circular opening, and above the opening is

a frusto-conical shell, L, provided with grinding-surfaces formed on its inner face. The lower and upper edges of the shell are reduced in size to form shoulders, and the shoulder at the lower margin rests on the margin of the opening in the top plate. A bowl or hopper, I, rests on the shoulder at the top of the shell L, and a series of bolts or rivets, M, connect the hopper and the top plate of the frame A, and thus bind together the frame A, the shell L, and the hopper I.

From the lower margin of the hopper spring three integrally-formed converging braces, K, whose inner ends support an integrally-formed vertical hollow post, J, which forms the bearing of the shaft of the grinding-cone. This shaft consists of three integrally-formed parts—viz., a lower cylindrical part, Q, journaled in the hollow post J, a square or otherwise non-cylindrical portion, P, above the cylinder Q, and a screw-threaded portion, F, above the squared space P and of less diameter than such squared part. On the lower end of the shaft is formed integrally a grinding-cone, consisting of a preferably hemispherical breaker, L', and a frusto-conical grinder, L", below the breaker, and on the lower margin of the cone is formed integrally an undressed or plain outward-extending horizontal annular flange, N, lying below the shell L and the space between said shell and the cone. On the square portion P of the shaft rests an internally-squared socket, H, formed integrally with an ordinary crank, O, and above the socket H is a nut, G, engaging with the screw F. The socket H is supported by the post J, which thus sustains the weight of the crank, the cone, and the cone-shaft, and the nut G and screw F form a means for raising or lowering the cone, and thus adjusting the space between the cone and shell. The raising or lowering of the cone also raises or lowers the flange N, and the raising or lowering of the flange impedes or retards the flow of ground material from the space between the cone and shell. If the flange be raised so far as to stop the flow of ground material entirely, the same particles are rubbed one upon another until they are ground to powder; or the flange may be lowered sufficiently to

allow the discharge of ground material unaffected by the operation of the flange. The raising or lowering of the cone thus has a double effect upon the fineness or coarseness of the product passed through the mill, and we have found that a more perfect regulation can be thus obtained than by the mere increase or decrease of the space between the grinding-surfaces.

The frame A, the shell L, and the hopper I may, if desired, be cast in one piece, and we have, in fact, manufactured a large number of these mills in that way; but the construction shown in the drawings presents advantages in casting and finishing which render it preferable in our opinion.

Having now described our invention and explained its operation, what we claim as new, and desire to secure by Letters Patent, is—

1. The herein-described coffee-mill, comprising the frame A, shell L, and hopper I, the braces K and hollow post J, formed integrally with said hopper, the grinding-cone L' L", suspended within said shell and provided with the undressed or plain annular regulating-flange N, and the cone-shaft formed integrally with said cone and journaled in said hollow post, substantially as shown and described, and for the purpose set forth.

2. The herein-described coffee-mill, comprising the shell L and hopper I, the braces K and hollow post J, the cone suspended within said shell and provided with the undressed or plain annular regulating-flange N, the cone-shaft consisting of the cylindrical portion Q, the square portion P, and the screw F, the socket H, fitting on said square portion of the cone-shaft and resting on the post J, and the crank O, formed integrally with said socket, and the nut G, engaging the screw F and adapted to raise and lower the cone, substantially as shown and described, and for the purpose set forth.

3. The combination of the shell L, the grinding-cone suspended within said shell and cooperating therewith, the undressed or plain regulating-flange N, formed on the lower margin of said cone, and means, substantially as shown and described, for supporting and for raising and lowering said cone.

In testimony whereof we have signed this specification in the presence of two subscribing witnesses.

EDGAR H. MORGAN.
CHARLES MORGAN.
